UNITED STATES PATENT OFFICE

2,617,693

TRACK AND GUIDE CONSTRUCTION

Dale Albert Stafford, Littlerock, Calif.

Application April 9, 1951, Serial No. 219,970

3 Claims. (Cl. 308—3.6)

1

This invention is a track and guide construction, and involves certain features of the fur-
ring strip disclosed in Patent Number 2,061,050,
dated November 17, 1936.

I have discovered that strips as shown in Fig.
5 of said patent when used in the construction
as set forth in the instant disclosure afford a
very practical part of track and guide means
whereby to facilitate the relative sliding move-
ment of mutually cooperative elements, say for
example of drawers slidably mounted in cabinets,
or in desks, and for panels shiftably supported in
walls or partitions, and for innumerable other
combinations where it is desirable to have quiet
and easy shift of one element as to or on another
structural element or elements.

An object of the invention is to provide a de-
vice which will accomplish the above stated func-
tions, and to provide a track and guide device
which is substantial, durable, light in weight, low
of manufacturing cost and in installation ex-
pense.

Further, an aim of the invention is to provide a
track and guide construction of such form of
elements as to require but very small installation
space; that is it is not bulky in form, and whose
parts may be closely nested for packaging, and
warehouse and store stocking, and transporta-
tion.

The invention resides in certain advancements
in this art as set forth in the ensuing disclosure
and having, with the above, additional objects
and advantages as hereinafter developed, and
whose constructions, combinations and details
of means and manner of installation and operation
will be made manifest in the following descrip-
tion of the herewith illustrative apparatus;
it being understood that modifications, variations,
adaptations and equivalents may be resorted to
within the scope, spirit and principles of the in-
vention as it is claimed in conclusion hereof.

Figure 1 is a sectional front elevation of a cabi-
net in which the drawer rail is installed.

Figure 2 is a perspective of the runner or shoe
member.

Figure 3 is a plan view of a portion of the rail
member, and Figure 4 is an end elevation of the
rail member.

Figure 5 is an end elevation of a form of the
shoe and the rail and guide members as applied
to an individual drawer supporting cleat.

Figures 6, 7 and 8 show a modification in which
the corrugations of the track member run from
side to side of the track.

The invention is here shown as incorporated in

2

a desk or cabinet having vertical components 2
which are jointed to horizontal parts such as
bars 3 between which latter is a conventional
drawer 4.

5 It is well known that such drawers are when
fairly loaded hard to pull or push because of the
friction set up by the customary flat, wide-faced
meeting or bearing surfaces, and further because
of poor fitting of the drawer there is tendency
10 of the drawer to jam.

To remedy these objections this invention pro-
vides for the installation of one or more of pairs
of mutual or cooperative shoe and rail assem-
blies one of which has functional movement as to
15 the other; and either of which may be the sta-
tionary part, the other the movable according to
the given case of installation.

In Fig. 2 there is shown, in detail, a shoe 5
formed of light-weight sheet metal, preferably,
20 bent to present right-angle flanges each of which
has, along its outer face, a medial longitudinal
traction wire 6. Fig. 1 shows such a shoe with
its re-entrant faces fitted and secured as by glu-
ing or otherwise to the bottom, inner corner of a
25 side 4s of a drawer so that one traction wire faces
inwardly and the other faces downwardly. It is
understood that such shoes will be affixed to both
sides of a given drawer, usually.

These applied shoes are adapted to slide longi-
tudinally along a respective track and guide de-
30 vice shown in Figs. 3 and 4 as comprising a mem-
ber 7 of angle-iron cross section to present side
and bottom flanges. Each of the sides of said
member is provided with a row of parallel beads
35 or corrugations 7c which run diagonally as to
the length of the flanges. Each of the corruga-
tions is medially, longitudinally perforated and
the edges of the perforations are each bent out-
wardly as to the ridge of its corrugation to form
40 short, stiff, parallel lips 7x.

The cabinet or desk as the case may be is pro-
vided with horizontal, front to rear, stationary
cleats 8 and Fig. 1 shows a track member 7 suit-
ably fixed to the top face of such a cleat, as by
45 gluing, in such a position that the shoe wires 6
will track along the rows of lips 7x of the fixed
track member. The bottom wire of the shoe will
transmit the vertical load of the drawer and the
side wire of the shoe will take the side thrust
50 reactions of the vertical flange of the fixed track.

Fig. 5 shows a modification of the track assem-
bly for use when there is a central track cleat 8c
in place in the desk or cabinet. In this form the
shoe has side flanges each provided with side
bearing wires 6s to engage cooperative track

lips $7x$ of a fixed track member $1a$ here of inverted, channel form and having a top row of lips to receive the vertical pressure wire of the shoe $5x$ which is of inverted, channel section. It will be seen that this form of channel track and guide device provides two-side control along the fixed cleat $8c$ and a top, vertical load track for stability and easy operation of the respective drawer.

In some constructions the track member may consist of a simple straight narrow strip $1s$, Figures 6, 7, and 8 having the beads or corrugations extending fully from side to side of the strip. And in this case the shoe member is also a straight strip $5s$ about equal in width to the width of its track strip $1s$. This constitutes a cheaper form of shoe and track than that shown in Figs. 2, 3 and 4, or in Fig. 5.

What is claimed is:

1. A track and guide assembly for relatively movable elements one of which bears the other operatively; said assembly including an elongated member and a relatively slidable member one of said members having a row of transverse, convex, parallel corrugations along one face and the other member having an elongated traction part operatively bearing on the top portions of the

said corrugations; the said traction part consisting of a section of wire fixed rigidly along its respective member and riding on a plurality of said corrugations.

5. The assembly of claim 1; and said corrugations being diagonal to the axis of the member and of the wire.

3. The assembly of claim 1; the ridges of the corrugations having punch holes with longitudinal outstanding bearing lips.

DALE ALBERT STAFFORD.
